PROCESS AND APPARATUS FOR RECLAIMING WASTE PRODUCTS IN THE MANUFACTURE OF WOOD-PULP.

1,326,414.

Specification of Letters Patent. Patented Dec. 30, 1919.

Application filed February 13, 1918. Serial No. 216,998.

To all whom it may concern:

Be it known that we, HUGH K. MOORE and JOHN T. QUINN, citizens of the United States, residing at Berlin, in the county of 5 Coos and State of New Hampshire, have invented new and useful Improvements in Processes and Apparatus for Reclaiming Waste Products in the Manufacture of Wood-Pulp, of which the following is a 10 specification.

This invention has relation to the recovery of the mineral or inorganic content of the liquor employed in the digestion of raw material in the manufacture of cellulose 15 fiber, although it is capable of wide application in various arts.

In order that the nature of the invention may be understood, we shall describe it particularly in relation to the manufacture 20 of sulfate pulp or soda pulp, in which, after the raw material has been subjected to a process of digestion, the fiber is separated from what is termed the "black liquor", the latter containing various valuable 25 inorganic products which it is desirable to reclaim or recover.

In U. S. Letters Patent No. 1,137,780, granted to one of the present applicants, Hugh K. Moore, there is illustrated and described 30 a process and apparatus for the treatment of the waste liquor for recovering the inorganic contents, in which, after a preliminary evaporation and concentration, the waste liquor is finally evaporated in a combined 35 steam boiler and smelting furnace, the carbonaceous mass burned, and the soda content recovered in its desired condition. Said Letters Patent show how the principles of Stefan's law may be applied to 40 the evaporation of the water and the recovery of the soda from the black liquor resulting from the so-called sulfate process. This law reduced to simple terms may be stated as follows: B. T. U. radiated per square 45 foot of radiating surface per minute = $2.66 \times 10^{-11} (T_1^4 - T_2^4)$ when T_1 is the absolute temperature of the body which radiates heat and T_2 is the absolute temperature of the body to which heat is radiated. It is evident 50 that, if one can reduce the amount of heat required to be radiated, one will get a direct benefit due to maintaining a higher average temperature in the radiating body which must necessarily lose in temperature

as it radiates heat. This increases the heat 55 radiated in a given space of time from the same surface area, or, to state it differently, one can cause the radiation of a greater quantity of heat from a smaller radiating surface in a given time. In the process and 60 apparatus described in the patent referred to, the radiant heat was obtained from two sources, to wit, by the combustion of a foreign fuel introduced into the furnace and by the combustion of the combustible content of the black liquor, it having been found up to that time that the introduction of a foreign fuel, such as gas, oil or powdered or pulverized coal or coke, was necessary for the production of the requisite 65 radiant heat. It was the intention, as expressed in the Letters Patent referred to, by the employment of a blast of air to atomize the fuel, and also by a blast of air or steam to atomize the lignin or black liquor 70 so as to reduce it to the finest possible particles and thereby to increase the evaporating and radiating surfaces of the particles of black liquor, but this was done, as stated, by pressure or by contact with a blast of 75 air or steam external to the particles themselves. Inasmuch, however, as the black liquor, at the time of its introduction into the furnace, is in a high viscous state due to its preliminary partial evaporation and 80 concentration, the particles thereof when subjected to a blast of high velocity, are necessarily large, relatively speaking, because of their high viscosity and great cohesive properties, and they consequently acquire 85 a high velocity, due to the air blast, through the space in which they were subjected to the radiant heat. Because of the rapidity with which these particles are projected through the heating space, they are 90 subjected in transit for only a minute length of time to radiant heat, and, because of their globular or compact condition, they acquire less heat by convection than if they were sub-divided into small particles. Furthermore, 95 because of the relatively heavy weight of the relatively large particles thus atomized by a blast of air, their velocity is necessarily high throughout their travel. In particles of the same material, the inertia 100 is as the cube of the diameter while the resistance of the air is as the square of the diameter. Consequently, when very small 105

2
diameters are approached, the resistance, due to the square of the diameter, overtakes and exceeds the inertia, which is as the cube of the diameter. Thus, as the diameter of the particles is decreased, the resistance of the air rapidly decreases the velocity thereof, and the distance which they travel. If the sub-division of the particles is continued, a particle may be obtained so fine that, while it will start with an initial high velocity, this velocity will be almost instantly checked, with a result that the particle might be said to float in the air. Furthermore, when the particles of relatively large size and heavy weight are subjected to both heat of radiation and heat of convection, although the peripheral portions of the particles may have had the water evaporated therefrom and the carbonaceous portions partially charred, there is contained in the middle of the particles a pasty mass through which the heat has not penetrated sufficiently to evaporate the water therefrom or to char it to a condition where it will be readily consumed. It was a consequence, therefore, of the process outlined in the previous patent that much of the lignin liquor reached the floor of the furnace without having had all of the water evaporated therefrom or becoming sufficiently charred so that it would be immediately consumed. Consequently there was a loss of radiant heat which might have been obtained in the particles had they all been brought to a radiant condition during their flight from the nozzle to the floor, or which might have been obtained if those which were brought to a temperature where they would radiate heat to a considerable extent in their transit were possessed of a greater radiating surface.

In the process and apparatus disclosed in the Letters Patent previously mentioned, the means of sub-dividing these particles was, as previously stated, entirely external. In carrying out said process, there were employed, in practice, first, various kinds of mechanical nozzles in which the centrifugal force of one portion of the liquor rotating 50 in contact with another portion of the liquor revolving in the opposite direction tended to strip the entire liquor into fine particles; and, second, flat nozzles designed to subdivide the liquor into a spray by a thin knife-like blast of air at high pressure and high velocity. These nozzles, while they did not meet the optimum conditions, yet were sufficiently successful that the whole operation of an industrial plant was based 60 upon their use. Nevertheless, as heretofore explained, though the particles produced by such nozzles were comparatively minute in relation to drops, they were relatively large in comparison with particles which would 65 be practically all surface and no volume.

Inasmuch as these particles were so relatively large, the heat of convection and what radiant heat would ordinarily come from the walls of a furnace, sublimed soda salts, and burning particles of black liquor, were 70 not sufficient to evaporate these particles in their entirety while in transit, and they arrived at the furnace floor in a more or less wet or pasty condition and tended to smother the fire thereon. In order to overcome these difficulties, an extraneous source of heat had to be supplied, and it was derived from the combustion of powdered coal, oil, or gas. In the use of gas, for example, the radiant particles were composed of illuminants, which, 80 heated to a high temperature by the burning gases and also burning themselves, added enough additional heat so that the particles of liquor would reach the furnace floor in a condition not to blanket the fire, 85 and the operation therefore could be continued. A plant, running successfully under these conditions, has been operated for several years.

Inasmuch as the blast of air, in order to properly disintegrate the black liquor, cannot practically be over 6/1000 of an inch in width, it will be readily seen that a slight wearing of these air nozzles greatly reduces the efficiency of the operation. That is, as 90 the air nozzle is greater in width, the tendency becomes greater to blow the black liquor in mass away rather than disintegrate or atomize it. In the so-called sulfate process, the dry residue from the black liquor on 95 evaporation contains something over 5,000 B. T. U. per pound. In the sulfite process, the dry residue contains something over 6,000 B. T. U. per pound. If, then, 2 pounds of black liquor containing 50% water were 100 blown into a furnace, theoretically, after evaporating 1 pound of water which would consume 1100 B. T. U., there would remain 3900 B. T. U. to be carried off in the combustion gases.

110 It is evident, from what has been said above, that, if the particles of lignin liquor can be sub-divided to such an extent that they will acquire a large part of the heat required for evaporation from the surrounding hot gases, the amount of radiant heat which will have to be added thereto may be very small.

The object of the present invention, in contra-distinction to the process disclosed in 115 said patent, is: first, to eliminate the necessity of using a foreign fuel for bringing about the combustion of the concentrated or partially evaporated black liquor; second, to increase the capacity of a furnace of a given 120 size and also to prevent losses due to the exterior radiation and conduction of heat from the furnace walls; third, to insure a greater evaporation of the water contained 125 in the particles of black liquor during their 130

transit by convected and radiant heat, thereby to bring about the charring and combustion of the carbonaceous portions of the black liquor contained in the particles while 5 in transit, and thus to furnish additional radiant heat for the evaporation of subsequent particles of the black liquor which have not reached the radiant stage; fourth, to reduce the weight of the particles of black 10 liquor and to increase their surface area, thereby to insure their heating by convection and to reduce the velocity of their travel through the heated gases in the furnace; and, fifth, to insure that the alkaline 15 effluent of the furnace is maintained high in sodium sulfid.

In explanation of the manner in which these objects are attained, we avail ourselves of other principles which may be briefly discussed. When considering the principles of 20 drying and evaporation, the percentage of inert gas determines the partial pressure on the liquor, and consequently the temperature effects vary in the same way as though the liquor were *in vacuo*. For example, in evaporating liquor in an atmosphere consisting of 20% steam and 80% air, the temperature effects would be the same as though the liquor were subjected to 24 inches (mercury) of vacuum. Again, water, if transformed into steam, occupies many times the space it previously occupied; for example, a pint of water, roughly speaking, when transformed into steam at 28 inches vacuum, 30 occupies 350 cubic feet or 21,000 times the space it occupied as water. We may utilize both of these principles in securing the desired results in the practice of our invention, by preheating the liquor to a high temperature 40 while maintaining it under pressure greater than the vapor pressure at that temperature, and then liberating it in a stream in a furnace, whereby we obtain a double explosive effect which disrupts the liquor internally and disintegrates it into the finest possible particles. As an illustration, let it be assumed that the liquor is heated to a temperature of 350° F., while maintained at a pressure greater than its 45 vapor pressure, and is then suddenly liberated in the furnace in which there is (for example) a partial pressure corresponding to 28 inches of vacuum (for instance an atmosphere of 93-1/3% inert gas, and 6-2/3% steam) under these conditions there would be an explosive action in the liquor due to the instant reduction in temperature from 50 350° F. to 212° F. at atmospheric pressure, and the further reduction to 100° F. due to the partial vacuum. While it may now be possible or practical to store sufficient heat to change all of the water of the black liquor into steam, it is practical to raise the liquor to a sufficiently high temperature while holding it under great pressure, to cause the

transformation of one-fourth or to one-third of such water into steam with the resultant explosive action. By generating a high explosive force in the liquor and injecting the liquor into the furnace, irrespective of a partial pressure therein (which may or may not exist, although we have reason to assume a partial pressure), the explosion which occurs causes the disintegration of the viscid material into minute particles, and the tearing apart of the lignin or cementitious cement thereof, so that, roughly speaking, the particles are very light and are practically all surface. Consequently, although the particles start at high velocity in the 70 furnace, their velocity is almost instantly checked and a large part thereof may be said almost to float in the air, and hence not only is the water evaporated, but the particles are charred, and the carbonaceous content is charred and actually consumed by combustion while in transit, thus furnishing a high degree of radiant heat for the following particles of black liquor. Under 75 these conditions, we have eliminated the necessity of using a foreign fuel, as the combustion of the combustible content of the black liquor in transit, and, as it reaches the furnace floor, furnishes the heat of radiation and convection for the evaporation of 80 the water content.

In carrying out the invention, we may use the following instrumentalities which are illustrated upon the drawing diagrammatically and conventionally,—1 is a storage 100 tank for partially evaporated and concentrated black liquor connected by valve 2 and pipe 3 to an agitator or mixer tank 4. 5 is a storage receptacle for finely pulverized salt cake which connects through removable diaphragms 6 and pipes 7 with the agitator tank 4. The diaphragm 6 is removable and may be made of various sizes so that the salt cake, which is to be mixed with the liquor, shall correspond to the 105 amount of liquor coming from storage tank 1. From the mixer tank 4 the mixture is drawn through pipe 8 by a pump 9 and delivered through pipe 10, and T 11, pump 12, by which said black liquor and salt cake are 110 forced through pipe 13 into coil 14 of the heater 15, and thence through the pipe 16 to header pipe or manifold 17 having valves 18 leading to pipes 19 projected into the furnace. The header 17 is also, by means of an 115 extension 20, connected with pump 21 and pipe 22 (having a check valve 221, if desired) to T 11. Steam is introduced into the chamber in the heater through a pipe 23 leading from a steam main not shown. The 120 drip from the heater 15 is delivered through pipe 24 to a trap 25 from which the condensed water is discharged. The pipe 19 from the manifold 17 is projected into the door of the furnace 26 which heats the 125 130

boiler 27. The particles of the black liquor, which is atomized into a spray indicated at 28, are largely consumed while in transit, while larger unconsumed but more or less 5 charred particles are deposited on the pipe 29 on the sloping floor of the furnace where they are completely consumed. The consumed gases and fine solid particles which 10 float in the furnace gases are carried through the flues of boiler 27 to a stack 281 through fan 291, and pipe 30, where they are either switched directly to the atmosphere through the extension 31 of pipe 30, or into a Cottrell precipitator 32 where the 15 particles are precipitated into a hopper 33 while the gases escape to the atmosphere through pipe 34. The smelted effluent is delivered from the furnace through spout 35 into agitator tank 36. As described, in the 20 previous Letters Patent, hereinbefore referred to, air at 3 to 5 pounds positive pressure is delivered through pipe 37 into the fire chamber below the spray to support the combustion. It may also be stated that the 25 black liquor, which runs into the storage tank 1, may be obtained in a partially evaporated and concentrated viscous condition from the evaporating system A, A, here represented conventionally as two-effect.

30 The operation may be briefly described as follows:

After the liquor has been mixed with a finely divided salt cake in mixing tank 4, it is necessary to keep the liquid in very 35 rapid circulation to maintain the salt cake in suspension, for it must be realized that, after the liquor has been concentrated to about a 55% solution, it will not then dissolve the requisite amount of salt cake. Consequently 40 all means for feeding the black liquor employed after the salt cake has been added must be such as to prevent the salt cake from settling. This is accomplished in the present case by keeping it at high velocity 45 during the remainder of its travel, and by passing it through the coil in the heater, wherein the centrifugal force of the liquor in traversing the coil and its constant change in direction keep the mixture well stirred so 50 that it becomes rapidly heated and does not stick to the wall of the coil or polymerize by prolonged contact with a given heat surface. Pump 9 and pump 12 are shown in the drawing in place of a two-stage or three- 55 stage pump, in order that the operation may be more clearly depicted. In practice, however, pumps 9 and 12 are preferably built as two-stage or three-stage pumps. Pump 9, in delivering the liquor through 60 pipe 10 into pump 12, builds up the required pressure; first, to maintain the velocity in the liquor coil 14, and, second, to maintain a pressure far above the corresponding vaporizing pressure of the liquid 65 at the temperature to which the steam en-

tering at pipe 23 would heat it. For instance, if we desired to heat the liquor to 335° F., we should maintain at all times on this liquor a pressure considerably over 100 pounds. This we now believe to be an absolute necessity and requirement, since, if the evolution of steam takes place in the system, there is a clogging of the system due to the depositing of solid products of the liquor. The excess liquor, which leaves the 75 manifold 17 as shown, goes through a pipe 20 to pump 21, thence through pipe 22, into the T 11, between pumps 9 and 12, or between the first and second stage of a two-stage pump. The drawing here illustrates 80 only one of the many methods in which this operation can be accomplished. For instance, pump 21 might be inserted in pipe line 16, or pump 9 might discharge into the pipe 20, thereby lowering the temperatures of the liquor passing through the pipes 21, 22, and T 11 to pump 12.

It will be seen that, by passing the liquor through the coil in the heater 14 and letting it escape through nozzle 19 into a surface, containing the hot and dry atmosphere, the liquor is automatically blown, exploded or disintegrated into the most minute particles, according to the principles hereinbefore stated. Pipe 19 is formed or provided at its end with a nozzle which is formed with a narrow elongated delivery port so that the explosive action practically takes place at the nozzle. This whole process, to secure the best results commercially, 90 requires the employment of a Cottrell or electrostatic precipitator, since the initial velocity of the fine particles of liquor is checked almost instantly and the particles more or less float in the furnace gases, a 100 greater proportion of them being so small and light that they float in the furnace gases through the boiler and exhauster and would eventually be lost in the atmosphere. This precipitator enables us to carry out 110 this process as it enables us to recover most of the soda in the fine atomized particles which tend to float away. In this connection, it may be observed that the preheating 115 of the liquor and its disruption as herein stated and the elimination of foreign fuel reduces greatly the gas flow through the boiler tubes and the Cottrell precipitator. This is advantageous in that it makes for a more efficient precipitation of the particles 120 of the soda content and diminishes the loss of heat through the furnaces.

In the process above described, it will be seen that the heat, which may be added to the liquor, is dependent first upon the temperature of the steam, and, second, upon the pressure, and requires care in the number of and the selection of the design and speed of the pumps employed. In order to overcome the difficulties in pumping this alka- 130

line liquor, we prefer to use high speed high pressure pumps having a long stuffing box containing a lantern gland. Into this lantern gland oil or water is preferably introduced to prevent the caustic liquor from injuring the packing. Of course in this case the use of brass is not allowable.

Referring again to the drawing, the liquor which comes from the manifold 17 through 10 the pipe 20 to pump 21, pipe 22, is pumped through 21 (which is used more as a circulating pump than for any other reason), and at the T 11 it meets the colder liquor coming from pump 9, so that at the reduced temperature 15 it passes through pump 12 through the heating coil where it is raised to the final desired temperature in pipe 16. In actual practice, the higher the temperature which can be given to this liquor the better 20 are the results secured in the furnace; first, because less heat need be furnished from the furnace proper to effect the evaporation of the water in the liquor, and, second, because of the greater explosive effect of the 25 resulting hot liquor. This liquor, when it enters the furnace, immediately gives up its stored up heat, and liberates a large part of its steam without any extraneous heat, the remaining water being evaporated by the 30 contact of the hot gases with the particles and by the radiant heat from the walls of the furnace and the minute burning particles, some of which take fire within a few inches from the nozzle. The result is that 35 practically all of the particles, as nearly as can be observed, take fire while in transit, and many of them have their combustible matter entirely consumed before they land on the furnace floor. The largest ones, 40 however, may land on the pile 29, which, however, instead of being more or less of a pasty mass, is a live bed of hot combustibles. This breaks off or slumps forward from time to time, and forms a more or 45 less charcoal-like bed through which the smelted inorganic matter runs to the spout 35 causing the sulfate content to be reduced to sulfids very much the same as if it were passed through a bed of charcoal.

50 It will be seen from the foregoing that, first, having supplied a large part of the heat from an outside source, second, having eliminated the air blast necessary to atomize the liquor, third, causing the burning 55 of the fine atomized particles in transit, and, fourth, obtaining more heat for evaporation by means of convection,—we have entirely dispensed with the necessity of employing a foreign fuel and the air required 60 to burn the same. We should, however, not regard it as a departure from the invention if the practice of our process were accompanied by the combustion in the furnace of a gaseous or other fuel.

65 In the process and apparatus described

in the previous Letters Patent, herein referred to, the volume of combustible gases was a great deal larger than the volume of the combustible gases in the present case and consequently caused an increased flow 70 through the boiler tubes. By cutting down the products of combustion, the velocity of the gases and products of combustion through the boiler tubes is slower, with the consequent saving of heat, or the prevention 75 of the loss of more heat through the flue gases. Furthermore, as it was not always possible in the previous process and apparatus to maintain in their entirety the predetermined oxidizing and reducing zones, 80 the large excess of air used to burn the combustible gases some times acted as an oxidizing agent in a detrimental oxidation of the sodium sulfid to sulfate.

Summarizing the foregoing, we mix the 85 liquor with salt cake, put it under pressure by means of pumps, heat it while under pressure in a heating coil, discharge it into the furnace under pressure, circulate the remainder of the liquor which does not go in 90 the furnace back to the pumping system, keep the rapid circulation up during the whole process and thus prevent precipitation of the salt cake, and keep the pressure up during the whole operation, to prevent 95 the liberation of steam in the circulating system. We explode the gases into the furnace by the heat internally contained therein, and produce particles so fine that they lose their moisture, first, by the heat 100 contained therein, second, by convection, and, third, by radiation, so that the particles take fire only a short distance from the nozzles, themselves furnishing heat which was formerly obtained from the illuminants furnished by the foreign fuel. The fine particles of valuable mineral content, which 105 float away in the gases leaving the furnace, are recovered in the Cottrell precipitator, and utilized. Preferably a balanced draft 110 is maintained in the furnace.

While we have in the subsequent claims defined the invention in the terms of a process and apparatus for the treatment of waste liquor resulting from the digestion of wood 115 in the production of cellulose, it will be understood that the invention is not necessarily limited to the treatment of such liquor but is capable of practice in the treatment of any liquid-containing material in which it is desired to evaporate the liquid content and consume the combustible content, quite irrespective of the recovery of any inorganic content, for it will be readily seen that we have provided, by the present invention, for 120 the utilization of the combustible portions of the initial substance in generating steam for supplying heat and power in a mill. In the present case, we also recover the soda content in a reducing atmosphere so as to se- 125 130

cure an effluent rich in sodium sulfid, and, while this is one of the valuable results of the invention according to the exemplification thereof herein illustrated and described, 5 we desire, by no means, to limit the invention thereto. Other liquid- and combustible-containing substances than those herein mentioned may be employed as the starting materials, as will be apparent to persons 10 skilled in the art, and many different kinds of such substances may be subjected to the treatment herein described even though the purpose be merely to consume them for the generation of heat or power, or for obviating the necessity of discharging them into 15 rivers or streams, or otherwise disposing of them.

We have not attempted to illustrate the various pressure gages, the thermometer 20 wells, valves and other accessories which are actually used in practice, for these may be employed where and when desirable.

Having thus explained the nature of our 25 said invention, and described a way of making, using and practising the same, although without attempting to set forth all of the forms in which it may be made, all of the modes of its use, or all of the ways in which it can be practiced, what we claim is:—

30 1. The herein described process of treating waste liquor which comprises exploding waste liquor in a furnace and subjecting the disintegrated particles to heat to cause the evaporation of the liquid content, and the 35 combustion of the combustible content thereof.

2. The herein described process of treating waste liquor which consists in subjecting waste liquor to heat while maintaining it 40 under a pressure greater than its vapor pressure at that temperature to generate an explosive force therein, liberating the liquor and thereby causing its disintegration into fine particles, evaporating the liquid content 45 of such particles, and burning the combustible content of such particles.

3. The herein described process of treating waste liquor which consists in subjecting waste liquor to high heat and pressure 50 to generate an explosive force therein, and then liberating the liquor in the presence of radiant heat to cause the disintegration of the liquor and the evaporation of the liquid content of the resultant particles, and burning 55 the combustible content of such particles.

4. The herein described process of recovering waste products which consists in subjecting waste liquor to heat and pressure to generate an explosive force therein and liberating the liquor, thereby causing its disintegration or disruption into fine particles, evaporating the liquid content of such particles, burning the combustible content of such particles, and recovering the non-combustible inorganic content of such particles,

5. The herein described process of treating waste liquor which comprises subjecting waste liquor to high temperature and pressure, circulating such liquor at high velocity, and liberating a portion thereof in the fire 70 chamber of a furnace to cause the disruption of such liquor into fine particles, the evaporation of the liquid content and the combustion of the combustible content of the particles so liberated.

6. The herein described process of treating waste liquor which comprises subjecting waste liquor to high temperature while maintaining it at a pressure greater than its vapor pressure at that temperature, circulating 80 such liquor at high velocity, then liberating a portion of such circulating liquor in a fire chamber to cause the disintegration or disruption thereof into fine particles by the explosive force thus generated, and subjecting such particles to a high degree of radiant heat.

7. The herein described process of treating waste liquor which comprises circulating 90 waste liquor at high velocity through a heater and by an explosive force generated therein disintegrating or disrupting such liquor into fine particles, and subjecting the disintegrated particles of liquor to radiant and convected heat.

8. The herein described process of recovering waste products which consists in partially evaporating and concentrating black liquor, subjecting the same to heat and pressure while maintaining it under a pressure 100 greater than its vapor pressure at that temperature to generate an explosive force therein and then liberating such black liquor in a furnace in finely disrupted particles, evaporating the liquid content and 105 burning the combustible content thereof, and recovering the soda content.

9. The herein described process in the treatment of black liquor which consists in heating black liquor to a vaporizing temperature while held under a pressure greater than its vapor pressure at such temperature to generate an explosive force therein and liberating such liquor in a spray of finely disrupted particles, evaporating the liquid 115 content and burning the combustible content of such particles, and recovering finely divided particles of mineral content by electrostatic precipitation.

10. The herein described process of treating black liquor which consists in partially evaporating and concentrating black liquor, disrupting the same in a furnace by an explosive force generated in such liquor, and evaporating the liquid content thereof by 125 the combustion of the combustible content of like liquor without the use of a foreign fuel.

11. The herein described process of treating black liquor which comprises mixing 130

5 finely divided salt cake and black liquor, circulating such mixture at high velocity and at great pressure, heating said mixture to a high temperature to generate an explosive force therein, liberating a portion of said mixture in the fire chamber of a furnace and exposing the particles thereof to radiant and convected heat generated by the combustion of previously liberated liquor in 10 such chamber.

12. A step in the process of treating waste liquor which consists in atomizing and disrupting the same by an internal disruptive force generated therein.

15 13. A step in the process of treating waste liquor which consists in atomizing the same by an internal disruptive force generated therein by relieving the pressure on the liquor after heating the liquor to a high temperature while under a pressure greater than the vapor pressure at that temperature.

20 14. The herein described process of treating black liquor which consists in disrupting black liquor in a heated atmosphere by an internally generated explosive force into fine particles, evaporating the liquid content thereof and charring the combustible content thereof by radiant heat generated by the combustion of like previously disrupted evaporated and charred particles.

25 15. The combination with a furnace and means for evaporating and concentrating black liquor, of means for heating such concentrated liquor to a high temperature, means for subjecting such heated liquor to great pressure to generate an explosive force therein without the generation of steam, and means for delivering such liquor in a stream or spray to said furnace, whereby when liberated in said furnace it explodes into fine particles.

30 16. The combination with a furnace, of a circulating system for waste liquor including one or more pumps for subjecting such liquor to great pressure and a heater for heating the liquor to a high temperature without the generation of steam when under such pressure, and a nozzle for liberating a stream of said liquor in the fire chamber of such furnace.

35 17. The combination with a furnace, of means for generating an explosive force in black liquor and exploding said liquor into finely disintegrated particles in the fire chamber of such furnace without the use of an air or steam jet, and burning the combustible content of such particles.

40 18. The combination with a furnace, and means for separating and recovering from the gaseous products of combustion soda particles escaping from such furnace, of means for evaporating and concentrating black liquor, means for confining and generating an explosive or disruptive force in such concentrated black liquor, means for

continuously liberating such black liquor into the fire chamber of such furnace in internally disrupted particles, whereby the heat generated by the combustible content of such particles evaporates the liquid content of the next succeeding particles, and means for recovering the smelted soda content of such particles.

45 19. The combination with a furnace, of a heater, a circulating system including pumps for circulating black liquor at a high velocity and great pressure through said heater and generating an explosive force in said liquor, means for mixing and delivering a mixture of black liquor and salt cake to said circulating system, and a nozzle connected to said circulating system for delivering said mixture so heated to the fire chamber of said furnace.

50 20. The combination with a furnace, of a circulating system for black liquor comprising conduits, pumps for subjecting said liquor to and forcing it at great pressure and high velocity through said conduits, and a heater for heating it to a high temperature to generate an explosive force therein, and a nozzle leading from said system into said furnace.

55 21. The combination with a furnace and a nozzle for delivering a stream of black liquor into the fire chamber thereof, of a circulating system for such liquor with which said nozzle is connected, said system comprising conduits, a coil, and one or more pumps for circulating and maintaining the liquor in the conduits and coil under high pressure, and means for heating said coil and liquor passing therethrough to a high temperature while the liquor is at a high pressure, whereby a disruptive or explosive force is generated therein.

60 22. The herein described process of recovering waste products which comprises generating an explosive force in and exploding black liquor within a furnace, subjecting the disintegrated particles to heat to cause the evaporation of the liquid content and the combustion of the combustible content thereof, and separating the soda from the waste products of combustion by electrostatic precipitation.

65 23. The herein described process of recovering waste products which consists in subjecting black liquor to heat and pressure to generate a disruptive or explosive force therein, then liberating the liquor to permit its disintegration and disruption into fine particles by such force, evaporating the liquid content of said particles, burning the combustible content of such particles, and recovering from the products of combustion a portion of the soda content by electrostatic precipitation.

70 24. The herein described process of recovering waste products which comprises

generating an explosive force in and exploding black liquor in the furnace, subjecting the disintegrated particles to heat to cause the evaporation of the liquid content and 5 the combustion of the combustible content thereof, smelting a portion of the soda content and recovering the same, and recover-

ing the finer particles of the soda content from the products of combustion.

In testimony whereof we have affixed our 10 signatures.

HUGH K. MOORE.
JOHN T. QUINN.
